UNITED STATES PATENT OFFICE.

RUSSELL ABNER FRISBIE, OF MIDDLETON, CONNECTICUT, ASSIGNOR TO THE J. & E. STEVENS COMPANY, OF CROMWELL, CONNECTICUT, A CORPORATION.

TOY PISTOL.

Application filed November 6, 1926. Serial No. 146,658.

My invention relates to improvements in toy pistols, of the form that is used for the discharge of a single or individual paper cap, and the object of my improvement is 5 to produce a toy pistol that is constructed and arranged so that there will be permitted the use of a relatively strong or stiff spring for operating the hammer so as to effect a relatively loud report from the impact on 10 the anvil, that has a trigger provided on a member that is separate from the hammer and located so as to provide relatively double or appreciably increased leverage so that discharge will be effected by a relatively 15 light pull and thus will be operable by a small child, and, furthermore, that is easily assembled by reason of the omission of a rivet or post as the pivot for said member, using in lieu thereof a knife-edge bearing 20 and which latter is located at the bottom margin or edge portion of the handle, thus permitting of the maximum length for said member and the corresponding gain in the leverage effect.

25 In the accompanying drawing:—

Figure 1 is a side elevation of a toy pistol embodying my invention.

Figure 2 is a plan view of the same.

Figure 3 is a side elevation with the left casing member removed.

Figure 4 is a fragmentary view corresponding to Fig. 3 with the parts in the cocked position.

My improved toy pistol comprises a casing 35 that is composed of a left member 10 and a right member 11 that are held together by means of a pair of rivets 12 and said members cooperate to provide as exposed and fixed parts the barrel structure 13; the handle 14 projecting downwardly from the rear of said barrel structure 13; the guard 15 extending around the junction 16 of said barrel structure 13 and the handle 14, and a sight 17 on said barrel structure 13. Also, 40 immediately at the rear of the barrel structure 13 is an opening 18 for admitting the paper caps or the like to the anvil 19 that is provided on the inside in the form of a projection from the side wall of the right member 11 and extending rearwardly from said opening 18 is a slot 20 for the hammer member 21.

The hammer member 21 has a flat plate-like body portion 22 that is located at the rear of the anvil 19; that projects upwardly

through the slot 20, and that is surmounted by a head 23 that is exposed and accessible for manipulation by the thumb for cocking.

On the front side of the body portion 22 is a hammer head 24 that is opposed to the 60 anvil 19 and cooperates therewith in effecting the discharge blow.

The pivotal connection for the hammer member 21 is of the knife-edge form, comprising a V-shaped point 25 that is seated 65 in a V-shaped groove 26 in a boss or projection 27 that is provided on the inside of the right member 11. The point 25 projects upwardly from the front edge of a downward extension of the body portion 22 which 70 is generally in the form of a hook that is hooked into or against the V-shaped groove or seat 26.

In the rear edge of the body portion 22, opposite the point 25, is a notch 28 that 75 serves as a seat for the positioning spring 29 and which receives the upper end of said spring 29. The lower end of said spring 29 is seated in a notch 30 that is provided in the lower edge portion 31 of the handle 14 and 80 in material that is integral with the right member 11.

The spring 29 tends to seat the hammer head 24 against the anvil 19 and is relatively 85 strong or stiff, by reason of the provision of a trigger member 32 that is in the form of a separate piece and that is constructed and arranged to cooperate with the hammer member 21 for firing.

In cocking, the hammer member 21 is 90 pulled rearwardly in opposition to the spring 29 to the limit provided by the slot 20 and is held in such cocked position by reason of the relative location of the pivotal and spring engaging points of the hammer member, as 95 usual, involving pulling beyond the center, on one side. In firing, the parts are moved by the center on the other side, as is understood, and then is followed by the action of the spring.

In the present structure the extension 33 of the body portion 22 that supports the pivotal point 25 has at the front edge a nose 34 that is opposed to and cooperates with a bearing edge portion 35 on the trigger 105 member 32 in effecting the firing.

The trigger member 32 is in the form of an elongated lever of the second class, the work point 35 being at about the middle thereof. The pivot therefor is of knife-edge 110

form comprising a V-shaped point 36 at the lower end that cooperates with the seat 37 that is located at or adjacent the lower edge 31 of the handle 14.

5 The upper end portion 38 of the trigger member 32 projects through the casing, through a suitable slot 39, into the space encircled by the guard 15 and terminates in the form of an enlargement 40 that is shaped 10 suitably to serve as the trigger proper that is engaged by the finger for firing.

It will be noted that the trigger member is substantially of the maximum length that is permitted and that can be operatively 15 housed within the shell-like housing space that is provided by the casing and that the trigger proper 40 is located in a relatively elevated position.

I claim as my invention:—

20 1. A toy pistol comprising a shell-like casing having an anvil, a hammer member pivotally supported by said casing and having a head for cooperating with said anvil, a spring for positioning said hammer member, 25 and operating to hold said hammer member in the cocked position, and a trigger member for releasing said hammer member from such cocked position, said hammer member having a contacting nose, said trigger member being 30 in the form of a lever of the second class and

having a bearing edge for cooperating with said nose, the pivotal connection for said hammer member and casing comprising cooperating knife-edge parts that are provided respectively on said hammer member and casing and that are adapted to be seated one against the other for the operative connection, and said spring serving also as the means for maintaining said knife-edge parts so seated one against the other.

2. In a toy pistol, a casing having an anvil, a hammer member pivotally supported within said casing, having an upper part that has a head for cooperating with said anvil, having a lower part that projects below the pivotal support and that has a tripping nose portion, and provided with an operating spring, a trigger member pivoted by its lower end adjacent the bottom edge of the casing structure, projected upwardly past said nose portion and having a bearing face that is opposed thereto, and having at its upper end a finger-portion that is exposed for firing, and said finger portion being located appreciably above said nose, whereby in firing the movement of the finger portion will be appreciably greater than that of the nose and the bearing face that is opposed thereto.

RUSSELL ABNER FRISBIE.
